FOOT OPERATED ELECTRIC SWITCH UNIT

Harry J. Collins, Jr., Bayside, Wis., assignor to Cutler-Hammer, Inc., Milwaukee, Wis., a corporation of Delaware

Filed July 19, 1961, Ser. No. 65,982

Term of patent 14 years

(Cl. D26—13)

Fig. 1

Fig. 2

Fig. 3

Fig. 4

Fig. 5

Fig. 6

FIGURE 1 is an isometric view of a foot operated electric switch unit, incorporating my new design;

FIG. 2 is an elevational view of one side thereof;

FIG. 3 is a front end elevational view thereof;

FIG. 4 is a top view thereof;

FIG. 5 is a rear end elevational view thereof; and

FIG. 6 is an elevational view showing the side opposite that shown in FIG. 2.

The dominant features of my new design reside in the portions shown in full lines.

I claim:

The ornamental design for a foot operated electric switch unit, substantially as shown and described.
